CONVEYOR MECHANISM

John D. Russell, Bradfordwoods, Pa., assignor to Joy Manufacturing Company, Pittsburgh, Pa., a corporation of Pennsylvania

Application January 11, 1956, Serial No. 558,452

8 Claims. (Cl. 214—41)

This invention relates to conveyor mechanism and more particularly to a conveyor mechanism especially designed for use in tunnel work for loading loose material such as muck into a train of mine cars.

The present invention is an improvement over that disclosed in my copending application Serial No. 302,527, filed August 4, 1952, now Patent No. 2,796,969, in that the structure is simplified and more compact.

An object of this invention is to provide an improved conveyor mechanism especially designed for use in tunnel work. Another object is to provide an improved conveyor mechanism for loading a train of mine cars with the conveyor mechanism mounted and guided by the same trackway as that which supports and guides the train of mine cars. A further object is to provide an improved conveyor mechanism made up of a series of articulated conveyor sections supported by skids engaging the rails of the tunnel trackway, with the skids having track providing surfaces over which the wheels of the mine cars may travel. These and other objects and advantages of the invention will, however, hereinafter more fully appear.

In the accompanying drawings there is shown for purposes of illustration one form which the invention may assume in practice.

In these drawings:

Figs. 1a and 1b, taken together, constitute a fragmentary side view of a tunneling apparatus with which the improved conveyor mechanism is associated.

Fig. 2 is an enlarged cross section taken on line 2—2 of Fig. 1a.

Fig. 3 is a somewhat schematic plan view of the improved conveyor mechanism illustrating the manner in which the conveyor sections may negotiate a curved trackway.

Fig. 4 is a detail vertical section taken on line 4—4 of Fig. 2, showing schematically the manner in which the wheels of the mine cars may pass over the conveyor skids.

Fig. 5 is a detail vertical section taken on line 5—5 of Fig. 4, showing one of the track engaging skids of the conveyor mechanism.

Fig. 6 is a view taken on line 6—6 of Fig. 5, showing a conveyor skid in side elevation.

Fig. 7 is an enlarged vertical section taken on line 7—7 of Fig. 3, showing in detail one of the cylinder and piston devices between adjacent conveyor sections.

Fig. 8 shows in plan one of the pairs of cylinder and piston devices.

The conveyor mechanism, generally designated 1, is shown associated with a tunneling apparatus embodying a conventional loading machine, generally designated 2, having an extensible drawbar connection 3 with the conveyor mechanism. An extensible conveyor 4 is connected between the conveyor mechanism and the loading machine and a wheeled truck 5 supports the rearward portion of the extensible conveyor as at 6. A conventional hoist 7 on the loading machine has cables 8 and 9 wound on its drums and operatively connected to a scoop or

2

scraper 10 and a sheave or guide pulley 11 attached to the working face serves as a guide for the forward cable. The hoist may be operated to draw in and pay out the cables to move the scoop 8 back and forth over the tunnel floor relative to a pile of loose material or muck designated M disposed on the tunnel floor near the working face. The scraper is operative to move loose material onto the nose 12 of the loading machine and the latter has an elevating conveyor 13 for moving the material upwardly and rearwardly to discharge onto the extensible conveyor 4. A tunnel trackway 14 has parallel track rails 15 over which the wheels 16 of the train of mine cars 17 are adapted to travel. The loading machine has retractable track engaging wheels 18 which may be moved into engagement with the track rails, in the manner fully disclosed in the above mentioned application.

Now referring to the detail structure of the conveyor mechanism, it will be noted that the latter is made up of a series of articulated sections coupled together as by connections 21 in end to end relation and each having bottom shoes or skids 22 slidingly engaging the rail treads. These shoes have depending inner flanges 23 which ride along the inner edges of the rail treads in such a manner to enable ready negotiation of the usual switches and frogs of the trackway while retaining the shoes on the track rails. Each shoe has oppositely inclined ramplike portions 24 having an upper track surface 25 overlying the rail treads and over which the wheels 16 of the mine cars may travel as the train of cars moves along the tunnel trackway beneath the series of upper conveyors 26 which overlie the cars in the manner also fully disclosed in my copending application Serial No. 302,527, above referred to. The shoes or skids support upright end frames 27 which extend oppositely at the sides of the mine cars (Fig. 2) and are provided with horizontal upper portions 27' which support the conveyors. The end frames may be rigidly connected in spaced apart relation as by connecting elements 28, desirably in the form of crossed struts or brace rods. Evidently the end frames of the conveyor sections may be rigidly connected in various other manners.

The conveyors each include an endless conveyor belt 29 and are arranged in cascade relation so that the discharge end of one overlies the receiving end of another in a well known manner. The wheeled truck 5 has a pivotal connection with the conveyor mechanism and a yoke member 30 has side arms 31 attached, as by pin and slot connections 32, to the adjacent end section of the conveyor mechanism. The yoke member is pivotally connected at 33 on a vertical axis, to the wheeled truck 5. The coupling connections 21 may assume various forms but herein for illustrative purposes may be similar to those disclosed in a copending application Serial No. 585,083, filed May 15, 1956, owned by the assignee of the present invention. These connections comprise a pair of extensible fluid devices in the form of parallel cylinder and piston mechanisms 34 comprising fluid cylinders 35 containing reciprocable pistons 36. The cylinders are pivotally connected at 37 to a frame 38 of a conveyor section for horizontal swinging movement, and the pistons 36 have piston rods 40 which are pivotally connected at 41 to an adjacent conveyor section. The ends of the cylinders are connected together by bypass conduits 42 and 43 and hydraulic fluid, preferably a light oil, contained in the cylinders may bypass freely through these conduits between the cylinders as the conveyor mechanism moves along a curved trackway, as shown in Fig. 3. Equal displacement of hydraulic fluid within the cylinders maintains constant pressure against the pistons in the cylinders, thus providing equal pull on each cylinder and piston device in all relative positions of the

pistons. It is therefore evident that there may be equal pull on each of the parallel devices 21.

The connections 21 are so arranged and constructed at the sides of the conveyor sections out of the path of the train of mine cars that they do not interfere with the under carriages of the mine cars. By the provision of these connections 21 the conveyor mechanism may be skidded along the track rails either forwardly or rearwardly and may move along a trackway which is curved (Fig. 3).

The conveyor mechanism may be moved along the tunnel trackway by the loading machine which is at that time supported on and propelled by its track engaging treads. At that time the extensible conveyor 4 and drawbar 3 are collapsed, and when the working place is reached the loading machine may run off the end of the trackway onto the tunnel floor and may operate over the floor independently of the trackway. The conveyor 4 and drawbar are extended as the loading machine moves forwardly from the tunnel trackway. The train of empty mine cars may be moved in any suitable manner, as by a locomotive, along the tunnel trackway and over the track engaging skids of the conveyor supports, with the mine cars located beneath the upper conveyors, as shown in Fig. 1a.

The scraper of the loading machine may be operated to gather the loose muck on the tunnel floor and to move it onto the extensible conveyor 4 which in turn discharges onto the conveyor mechanism, and the loose material is moved along the upper conveyors to discharge progressively into the mine cars as the train of cars is shifted beneath the discharge end of the conveyor mechanism, until the cars of the entire train are filled. The loaded train may then be moved along the trackway from beneath the conveyor mechanism while the latter remains in a relatively stationary position on the trackway.

As a result of this invention an improved conveyor mechanism is provided for loading a train of mine cars in tunnel work. By mounting the conveyor mechanism on skids which ride along the track rails the structure is made more simple in design and relatively low in overall height, while the desired maneuverability is retained. The conveyor supporting skids engaging the rails of the same trackway as that which supports and guides the train of mine cars have upper track providing surfaces so that the car wheels may readily travel over the skids as the train of cars moves along the trackway beneath the upper conveyors. The improved conveyor structure is rugged and durable in design, well adapted to withstand the severe conditions of service in tunnel work. Other advantages will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. A conveyor mechanism for tunneling work comprising a conveyor frame structure carrying an upper conveyor means provided with a discharge end and having relatively short bottom shoes slidable along the rails of a tunnel trackway, said frame structure adapted to receive a train of cars therein beneath said conveyor means and said shoes having upper track providing surfaces directly above the rail treads over which the wheels of a mine car may move as the mine car travels along the tunnel trackway beneath the discharge end of said upper conveyor means, said shoes being spaced substantial distances apart lengthwise of the mechanism so that the car

within the frame structure is in the main supported by the tunnel trackway.

2. A conveyor mechanism as set forth in claim 1 wherein said shoes have depending flanges engaging the inner edges of the rail treads for retaining said shoes in guided position on the track rails.

3. A conveyor mechanism for tunneling work comprising a series of articulated conveyor frame sections each carrying an upper conveying means, said conveying means provided with a discharge end, said frame sections being centrally open lengthwise thereof and arranged to receive a train of cars therein beneath said conveying means, said frame sections having relatively short bottom shoes slidably engaging the rails of the tunnel trackway, said shoes having upper track surfaces overlying the rail treads over which the wheels of the cars of a train may pass as the train moves along the tunnel trackway beneath the discharge end of said conveying means, said bottom shoes being spaced apart substantial distances lengthwise of the mechanism so that the cars within the frame sections are in the main supported by the tunnel trackway.

4. A conveyor mechanism as set forth in claim 3 wherein said bottom shoes have depending flanges engaging the inner edges of the rail treads for retaining the shoes in guided position on the track rails.

5. A conveyor mechanism as set forth in claim 3 wherein coupling connections are provided between said conveyor frame sections for connecting said sections together for movement back and forth along the tunnel trackway, said coupling connections arranged at the outer sides of said frame sections to provide space for the passage of the mine cars within said frame sections between said connections as the train travels along the tunnel trackway.

6. A conveyor mechanism especially designed for tunnel work comprising upright end frames spaced apart longitudinally of the mechanism and rigidly connected together, and upper conveying means carried by said end frames, the conveyor mechanism adapted to receive a train of mine cars therein beneath said conveying means, said end frames having relatively short bottom shoes slidably along the rails of the tunnel trackway, said shoes providing upper tracks above the rail treads for the wheels of the mine cars as the latter travel along the trackway beneath said conveying means, said shoes being spaced a substantial distance apart longitudinally of the mechanism so that the cars within the mechanism are in the main supported by the tunnel trackway.

7. A conveyor mechanism as set forth in claim 6 wherein a series of conveyor frame sections are pivotally connected together and coupling connections are provided between said frame sections permitting lateral turning of said frame sections as they slide along a curved trackway, said coupling connections arranged at the sides of said frame sections out of the path of movement of a train of mine cars moving along the tunnel trackway beneath said conveying means.

8. In a tunneling apparatus, the combination with a mine car adapted to travel along a trackway laid on the tunnel floor, of a conveying mechanism for conveying loose material dislodged from the tunnel face to the mine car comprising a conveyor frame arranged to receive the mine car therein beneath said conveying mechanism and having relatively short bottom skids engaging and slidably along the treads of the track rails and over which the wheels of the mine car may travel whereby the car may move longitudinally relative to said conveying mechanism while the latter remain supported on the trackway, said bottom skids being spaced a substantial distance apart longitudinally of the apparatus so that the car is in the main supported by the tunnel trackway.
